UNITED STATES PATENT OFFICE.

WILLIAM WILKINS, OF OAKLAND, CALIFORNIA.

SANITARY GARBAGE CAN.

Application filed August 17, 1926. Serial No. 129,728.

The present invention relates to improvements in sanitary garbage cans and has for its particular object to provide means whereby a garbage can may be properly ventilated and further means allowing a deodorant to be discharged into the garbage can at desired times and in desired amounts so as to prevent obnoxious odor from contaminating the air around the garbage can. Further objects and advantages of my invention will appear as the specification proceeds.

The preferred form of my invention is illustrated in the accompanying drawing in which Figure 1 shows a vertical section thru my garbage can and

Figure 2 a horizontal section taken substantially along line 2—2 of Figure 1.

While I have shown only the preferred form of the invention, I wish to have it understood that various changes or modifications may be made within the scope of the claims hereto attached without departing from the spirit of the invention.

In its preferred form, my garbage can comprises a disked bottom 1, a cylindrical wall 2 rising therefrom, and a removable cover 3 provided with a depending flange 4 adapted to be telescoped into the top of the garbage can. For ventilation of the can, I provide a series of perforations 6 adjacent the bottom of the garbage can and a second series of perforations 7 adjacent the top thereof.

The cover 3 of the garbage can has a container 8 depending from the bottom face thereof, preferably in concentric relation to the flange 4. The said container is preferably permanently fastened to the top by means of rivets 9 or in any other suitable manner. The container is formed with a slot 11 in the side thereof which latter may be closed by means of a slide 12 running in a guide 14 and adapted to be operated by means of a handle 14 extending from the slide in radial direction.

The bottom of the container which is preferably made flat is perforated, preferably by means of radial lines of holes 16 and a disc of substantially the same size as the bottom of the container is pivoted thereto as shown in 17 so as to be revolvable over the said bot-

tom. The disc is also provided with a plurality of perforations 18 arranged so that they may be made to register with the perforations 16 when the disc is turned into 55 registering position. A slight turn of the disc causes the holes therein to be moved out of registry so that the bottom of the container is then closed. The disc may be operated by means of a short 60 handle 19 rising perpendicularly from the margin thereof and extending thru a slot 21 in the top of the cover, the slot being sufficiently long to allow the disc to be moved from registering to non-registering positions 65 and vice-versa.

The advantages of my sanitary garbage can are apparent from the above description. The perforations 6 and 7 near the bottom and near the top allow the can to be freely ventilated. A deodorant may be introduced into the container from the side and any desired amount of the deodorant may be dropped upon the contents of the garbage can by operating the handle 19.

I claim:

1. The combination with a garbage can of a removable top, said top having a cup-shaped container depending from the bottom face thereof, a slot in the side of said container for allowing the fumes of the contents of said container to penetrate the interior of the said can, a slide disposed in said slot, and means on said slide for selectively causing the same to cover or uncover said slot, 85 and a rotary cutout member pivoted to the bottom of said container having apertures therethru adapted to register with apertures on the bottom of said container, and having a handle attached thereto extending thru 90 said cover, as and for the purpose specified.

2. The combination with a garbage can having perforations adjacent the top and bottom thereof, of a removable top, a container depending from the under face of 95 said top, said container having a bottom and annular side wall, there being an arcuate slot in said annular side wall for allowing the fumes of the contents of said container to penetrate the interior of said can and an arcuate guide member disposed in said slot, said guide member acting as a closure 100

for said slot, means for operating said guide member, there being apertures in the bottom of said container, and a rotary cutout member having apertures therethru adapted to register with apertures in the bottom of said container, and a handle attached to said rotary cutout extending thru an arcuate slot

in said cover, whereby said rotary cutout may be operated to sift disinfectant into the interior of said container. 10

In testimony whereof I do hereby affix my signature.

WILLIAM WILKINS.
